UNITED STATES PATENT OFFICE

THEODOR ENGEL, OF WIESBADEN, GERMANY

DEVICE FOR AIDING IN MANUFACTURING ARCH SUPPORTS

Application filed December 6, 1929, Serial No. 412,141, and in Germany June 11, 1929.

The present invention relates to a device whereby the under-contour of the feet may be measured with exactitude in order to permit the accurate manufacture of an arch support. Heretofore, foot contours have been measured by means of plaster-of-Paris moulds. The main disadvantage of such moulds is that it is not possible to use the same as an anvil or similar former or shaper, permitting a metal plate to be pressed, hammered or formed into shape thereon.

The object therefore, of my invention is to provide a device which will not only accurately measure the under foot surface but which can be fixedly held in its position of adjustment after the foot measurement has been obtained to enable future comparison of the arch support made with the original measurements taken.

A further object of my invention is to provide a means which will form, simultaneously with the taking of the foot measurement, an anvil or other support on which the arch support may be pressed, hammered or otherwise formed into shape.

A still further object of the invention is to provide a means whereby the arch of the foot may be readily measured in spite of the fact that it might be deformed or if the leg be weak-jointed, the measurable degree of the knock may be taken into consideration.

With these objects and such other objects as may hereinafter appear, in view, I have devised the particular arrangement of parts set forth below and more particularly pointed out in the claims appended hereto.

Reference is to be had to the accompanying drawings, in which

Figure 1 is a side elevation of my improved device;

Figure 2 is an end view of the same;

Figure 3 is a plan view of the same;

Figure 4 is a side elevation of the structure showing the manner in which the foot measurements are taken;

Figure 5 is a view of the lower portions of the device showing the manner in which the same may be used as an anvil;

Figure 6 is an end view of the apparatus

during the forming process for a weak-jointed leg; and

Figure 7 is a sectional view of the upper portion of the structure as shown in Figure 6.

Throughout the various views of the drawings, similar reference characters designate similar parts.

In the embodiment of my invention disclosed in the accompanying drawings, I show an upper frame consisting of side members *a*, *a*1 and four downwardly depending legs *b*. The frame thus formed is provided with a pair of spaced plates *d*1 and *d*2 extending between and supported by the legs *b*. At *e* is shown a plurality of closely spaced pins which are provided at their upper ends with heads 2, these heads being located adjacent to one another and co-operating to form a foot surface or bed.

The pins *e* are adapted to be freely movable through openings provided in the plates *d*1 and *d*2 and are normally held with their heads extended for a considerable degree above the plate *d*1 by the pressure of springs *f* which surround each one of the pins *e*.

Located between the plates *d*1 and *d*2 are slidable wedging plates *g*1 and *g*2, said plates having holes *i* (Figure 7) partly aligned with the holes provided in the plates *d*1 and *d*2. The wedging plates *g*1 and *g*2 are provided with handles 3 to enable them to be forced in opposite directions to grip the pins *e* and prevent the same from longitudinal displacement once the foot contour has been obtained.

At B-B is a frame similar to that just described, the same being provided with pins *E* which pass through spaced plates *D*1 and *D*2 and having wedging plates *G*1 and *G*2.

It will be seen that the pins *E* have their heads extending downwardly and their opposite ends 4 abutting against the similar ends of the pins *e*. Sockets *K* are provided on the posts *B* so that the posts *b* on the frame *a* may fit in said sockets and the frame *a* held directly over the frame *b* whereby the pins *e* and *E* may be held in direct alignment.

The two frames *a* and *B* in their superposed position are held on supports *m* whose upper ends terminate in sockets *K*1 into which the lower ends of the post *B* fit. The posts *m*

rest upon a flat support *n* which has its side edge pivoted at *s* to an under-support *p*.

From the foregoing, the manner in which my device is used will be readily understood.

5 The foot to be measured, is placed firmly upon the heads 2 provided on the pins *e* and is firmly pressed thereon. These pins *e* move downwardly against the pressure of their springs *f* and closely conform to the under-curvature 10 of the foot. The wedging plates *g*1 and *g*2 are then brought into action and when forced in opposite directions, serve to grip the sides of the pins *e* and hold the same in their position of adjustment. The pins *e* now being 15 forced downward by the pressure of the foot act to similarly force downward the pins *E* which may then also be gripped and held in their adjusted position by the pressure of the wedging plates *G*1 and *G*2. Thus, the parts 20 assume the position shown in Figure 3. It will be there seen that the heads 2 on the pins *a* give the correct under-contour of the foot while the heads on the pins *E* give a reverse replica of such contour.

25 The frame *B* carrying the pins *E* may then be removed from its support and upturned as shown in Figure 5 where it will be seen that the heads on the pins *E* form an anvil on which the metal sheet which makes the arch support may be hammered, pressed or moulded 30 into shape. The reverse replica of the arch may be taken from the heads on the pins *e*.

35 In Figures 6 and 7, I disclose the operation of measuring an arch of a weak-jointed leg. In such case, the bottom member *n* is adjusted by means of an adjusting screw *7* according to the measurable degree of the knock by means of a plumb line *s* and scales 40 *r*1 and *r*2 and then the forming or moulding of the arch of the foot is formed in a manner set forth.

45 While I have shown one embodiment of my invention, it is obvious that the same is not to be restricted thereto, but is broad enough to cover all structures coming within the scope of the annexed claims.

What I claim is:—

1. In a device of the class described, a 50 support, a plurality of spring-pressed rods held thereon, the upper ends of said rods adapted to conform to the shape of a foot placed on them, a second set of rods held below the spring-pressed set, the lower ends 55 of which are provided with heads and adapted to form a reverse replica of the shape of the foot placed on the spring-pressed rods.

2. In a device of the character described, a 60 plurality of spring-pressed conformable members against which the sole of the foot is adapted to be pressed, a support in which the same are held, means for locking said members against longitudinal movement through their support when required, and a 65 plurality of movable members located below

those on the support and adapted to be shifted to correspond thereto by foot pressure on the conformable members, and means for locking the last-mentioned members in the positions to which they are shifted.

70 3. In a device of the class described, a frame for taking foot sole measurements for arch supports, a plurality of spring-pressed pins adapted to be independently depressed by foot pressure, and means for holding the frame inclined during the imposition of foot pressure to take into consideration the measurable degree of the knock of weak-jointed legs during the measuring operation.

75 Signed at Frankfort a/m, Germany, this 14th day of November, 1929.

80 THEODOR ENGEL.
